United States Patent Office.

ORSEMEUS M. STILLMAN, OF WESTERLY, RHODE ISLAND.

Letters Patent No. 74,443, dated February 11, 1868.

IMPROVEMENT IN GIG FOR CLOTH.

The Schedule referred to in these Letters Patent and making part of the same.

TO ALL WHOM IT MAY CONCERN:

Be it known that I, ORSEMEUS M. STILLMAN, of Westerly, in the county of Washington, and State of Rhode Island, have invented a new and useful Improvement in Cloth-Gig; and I do hereby declare that the following is a full, clear, and exact description thereof, which will enable those skilled in the art to make and use the same, reference being had to the accompanying drawings, forming part of this specification, in which—

Figure 1 represents a side view of my improved cloth-gig.

Figure 2 is a vertical central cross-section through the raising-cylinder and cloth-rolls.

Figure 3 is a partial top view, exhibiting transverse endless aprons for gigging crosswise of the cloth.

Figure 4 is a detached view of a cloth-beam, partly in section, showing the mode of its connection, to permit attaching and detaching readily, for reversing the action of the teazles on the cloth.

Similar letters of reference indicate corresponding parts.

This invention relates to improvements in the construction and operation of gigs, for raising the nap upon woollen cloths, and consists in simple devices for bringing the cloth into contact with one raising-cylinder at four distinct points or places simultaneously, whereby nearly four times as much work is performed at the same time; and also, in connection therewith, a system of cross-gigging from one edge or selvedge of the cloth to the other, instead of the ordinary mode of teazling from the centre of the piece to the edges, in opposite directions. In connection with these devices for gigging the cloth longitudinally at four places on the raising-cylinder at a time, are simple devices for graduating the bearing of the cloth against the teazles while passing over this raising-cylinder, and for lifting it clear of the teazles when required; and further, for changing the cloth-beams or winding-rolls end for end in the machine, and thus reversing the operation of teazling without unwinding the cloth, as practised generally with the ordinary gig, for the purpose of raising the nap in the opposite direction on the cloth.

A is the raising-cylinder, hung in a suitable frame, B, on the axis *a*, connected with any motive-power, as desired. Below the raising-cylinder, on its opposite sides, are placed the winding-rolls or cloth-beams *b b'*, and around the cylinder, near to the surface, are placed five small guide-rollers, *c c'*, suspended to the frame B. The cloth-beams *b b'* receive motion from the axis *a* by cog-gearing at one end of the cylinder, connected therewith, as shown in fig. 1, *d* being a pinion on the axis *a*, engaging a spur-wheel, *d'*, that gears into a spur-wheel, *d''*, on the axis *g* of one of the cloth-beams, *b'*, and by means of an intermediate wheel, *e*, actuates the spur *d''*, on the axis *g* of the other cloth-beam, *b*. The cloth-beams *b b'* are each formed with square recesses or mortises in the ends, which fit alike on the ends of the axes or journals *g g'*, in such manner that they may be taken off and changed end for end in place of each other. For this purpose, the journals *g g'*, on the ends opposite the driving-gear, are made to be taken, when necessary, out of their bearings, *h h'*, in which they are held by buttons or catches, *k*, as shown clearly in fig. 4, or may be held in place in any suitable manner. The piece of cloth to be teazled is wound upon the front beam, *b*, and passes over the raising-cylinder A, resting on the guide-rollers *c c'*, in such manner that the surface of the cloth shall touch the teazles, for napping, at several points between the rollers, as shown in fig. 1. The cloth also bears upon and passes under an extension-roller, *m*, at the back part of the raising-cylinder, turning at right angles, and passing horizontally over two endless aprons or cross-bands, *o o'*, fig. 3, (which travel in opposite directions,) and thence, over the rollers *n n'*, to the cloth-beam *b'*, on which it is wound, or between perpetual rolls, when such are used. The cross-bands *o o'* take their motion from reverse driving-pulleys *p p'*, one of which, *p'*, is hung on a shaft, *q*, and the other one, *p*, on the sleeve *s*, upon the shaft *q*, actuated by bevel-wheels *t t'* respectively, which gear into the same bevel-wheel, *r*, or may be actuated in any other suitable manner. Opposite the pulleys *p p'*, the cross-bands *o o'* bear on counter-pulleys *p'' p'''*, the whole being supported by a frame, C. The cross-bands *o o'* will carry teazles or cards, for the purpose of napping or raising the fibre of the cloth crosswise, from side to side, or from selvedge to selvedge, as it passes over the cross-bands, which travel in opposite directions, and thereby counteract the movement of each other, and, in connection with the extension-roller *m*, hold the cloth evenly and smoothly while it is being teazled transversely. The cross-bands *o o'* are supported and borne upwards against the cloth by a board, *w*, which is adjusted by raising or lowering, as desired, to regulate the bearing of the teazles or cards. For regulating the bearing of the cloth against the teazles on the raising-cylinder, two of the guide-rollers *c c'* are made adjustable.

They are each hung in the ends of sliding racks, *i i*, which are moved by pinions, *j j*, at each end, working in worms or screws, *x x*, on the same shaft, *z*, at one end of the cylinder. By the elevation or depression of these two rollers, the cloth is raised or lowered at four places, to adjust its bearing in contact with the teazles on the raising-cylinder, and the guide-rollers may be elevated, so as to raise, entirely clear of the teazles, the aprons, which are usually attached to the cloth, for the purpose of starting the work and of teazling at the ends. After the cloth has been passed over the raising-cylinder back and forward a few times, and is wound upon the back winding-roll *b'*, the winding-rolls *b b'* are both taken from their axes, as previously described, and shifted in their places, end for end, and thus the operation of teazling will be conducted in an opposite direction to that previously performed, without unwinding the cloth. The guide-rollers *c c* may be so arranged that the cloth shall come in contact with the raising-cylinder in three places only, instead of four, as above described.

Having described my invention, I claim as new, and desire to secure by Letters Patent—

1. The combination and arrangement of the cross-bands *o o'*, reverse driving-pulleys *p p'*, counter-pulleys *p'' p''*, adjusting-board *w*, shaft *q*, tubular shaft *s*, bevel-wheels *t t' r*, as herein described, for the purpose specified.
2. The arrangement of the cylinder *A*, rollers *c*, racks *i*, pinions *j*, shaft *z*, worm-wheels *x*, rollers *m n n'*, reversible cloth-beams *b b'*, and gear-wheels *d d' d'' d'''*, as herein described, for the purpose specified.

O. M. STILLMAN.
